(57) **CLAIM**

The ornamental design for a cord lock, as shown and described.

DESCRIPTION

The cord lock in combination with an elastic cord is used for bundling cables.

FIG. 1 is a perspective view of a cord lock showing my new design;

FIG. 2 is a left side elevational view thereof;

FIG. 3 is a front elevational view, the opposite side being a mirror image thereof;

FIG. 4 is a right side elevational view thereof;

FIG. 5 is a bottom plan view thereof;

FIG. 6 is an environmental, perspective view thereof; and,

FIG. 7 is an environmental, top plan view thereof.

The broken lines are for illustrative purposes only and forms no part of the claimed design.

CERTIFICATE OF CORRECTION

PATENT NO. : D604,589 S
APPLICATION NO. : 29/323694
DATED : November 24, 2009
INVENTOR(S) : Benny Johansson

Page 1 of 4

It is certified that error appears in the above-identified patent and that said Letters Patent is hereby corrected as shown below:

The Title page, showing an illustrative figure, should be deleted and substitute therefor the attached title page.

Delete drawing sheets 1-2, and substitute therefor the drawing sheets, consisting of figs. 1-7 as shown on attached pages.

Signed and Sealed this
Fourth Day of September, 2012

David J. Kappos
Director of the United States Patent and Trademark Office
